(57) **CLAIM**

The ornamental design for an electronic tracking device, as shown and described.

DESCRIPTION

FIG. 1 is a top, front, right side perspective view of an electronic tracking device according to my new design;

FIG. 2 is a top, rear, right side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken line showing is included for the purpose of illustrating portions of the electronic tracking device and forms no part of the claimed design.
